UNITED STATES PATENT OFFICE.

WALKER L. PERKINSON, OF LOUISVILLE, KENTUCKY.

DOOR-CHECK.

No. 896,146.

Specification of Letters Patent.

Patented Aug. 18, 1908.

Application filed November 22, 1907. Serial No. 403,330.

To all whom it may concern:

Be it known that I, WALKER L. PERKINSON, a citizen of the United States, residing at Louisville, in the county of Jefferson and 5 State of Kentucky, have invented a new and useful Door-Check, of which the following is a specification.

This invention relates to that class of devices used for checking and holding open 10 doors; and has for its object to provide a horizontally rotatable device to be fastened to the floor or overhead in the path of a moving door near its edge where it will be struck by the door and caused to turn and automatically engage the door on each side and 15 retain it in open position until disengaged.

A further object of the invention is to provide a device that is ready at all times to engage the door when pushed against by it that 20 does not require to be set, is simple cheap and noiseless, made of few parts, and does not deface the door nor mar the appearance of a room by its presence therein.

With these and other objects in view the 25 invention consists of the novel construction, combination and arrangement of parts hereinafter described and set forth in the attached claims.

In the accompanying drawing: Figure 1 is 30 a perspective view of the device showing it in use. Fig. 2 is a view partly in elevation and partly in longitudinal section. Fig. 3 is a top plan view of the swinging plate. Fig. 4 is a perspective view of a detail, Fig. 5 is a 35 view showing a modified form of pivot bearing. Fig. 6 is a view showing a further modification of the pivot bearing. Fig. 7 is a diagrammatic view illustrating the means employed to prevent the door striking the device on dead center.

Similar reference numerals are used for the same parts on all the figures.

The numeral 1 indicates a flat plate, or a plate flat in the center with slightly raised 45 ends 2, on the upper face of each of which ends is secured a knob or buffer 3. A hole is bored through the center of the plate, see Fig. 5, for a pivot screw 5 by means of which the device is attached to the floor in the path 50 of a moving door. A washer 6 is placed between the plate 1 and the floor to form a bearing surface for the plate and to reduce friction.

In the preferred form of the pivotal connection, shown in Figs. 2 to 4, the washer 6 has a boss 7 on its upper face with beveled

edges 8 which extend into the enlarged opening 4 in the plate, and a series of balls placed in the space between the boss and the edge of the opening. Over the balls is a washer 9 60 slightly larger than the opening 4 and the screw 5 passed therethrough, through a hole 10 in the lower washer 6 and into the floor.

A more simple construction is shown in Fig. 6. Here a washer 11 is fitted in the opening 4 in the plate 1 and rests on the large washer 6. The screw 5 and washer 9 hold the parts together as shown in the preferred form, the plate 1 rotating about the washer 11 as a pivot.

Each of the knobs or buffers 3 has a cylindrical neck 12 topped with an enlarged head 13 having a hemispherical edge 14, in the periphery of which is made a semi-circular horizontal groove 15 for a rubber ring 16 75 projecting beyond the side of the head and forms an abutting surface for the door. Through the neck and head of each knob 3 is a cylindrical bore 17 containing a rigid sleeve 18 around which the knob easily turns.

Extending upwardly through a hole 19 in an end 2 of the plate 1 and through the sleeve 18 above its upper end is a screw bolt 20, held in place by a nut 21 threaded on the end of the screw and bearing on the upper end of the sleeve 18, holding it tightly against the plate 1. This construction forms a strong pivot for the knob, enabling it to receive severe blows from a door without bending it. The bore 17 in the knob is 90 counter bored at the top at 22 to permit the use of a nut large enough to extend over the bore and retain the knob on its pivot. A washer may be placed between the nut and the sleeve if desired.

A door check such as described is, when in use, fastened to the floor near the wall in position to have one of its knobs struck by the side of a door near its edge when the door is opened to its full extent. When a knob is struck by the door the plate 1 turns to the right or left, depending upon which side of the center of the shortest line drawn from the axis of the plate to the door, the knob may be. If the knob struck turns towards the edge of the door, the other knob will be carried towards the door and on being struck, it will be returned by the continued movement of the door, rotating the plate until the other knob is carried to the other side of the door, thus catching the latter between the two knobs. If the knob struck turns toward

the hinged edge of the door, the other knob will be carried around to the front and the door will again be caught between the knobs.

To prevent the shock and jar, and perhaps injury to the door check should it be struck by the door when the plate 1 is perpendicular thereto, a small triangular or semi-circular block 23 is fastened to the door a little to one side of the point where the door would strike the knob 3 as shown in Fig. 7. This will insure the operation of the door check at all times.

Having described my invention what I claim as new and desire to secure by Letters-
15 Patent is:—

1. A door check comprising a plate pivoted intermediate its ends, and a buffer pivoted on each end of said plate said buffers being in a straight line with the pivot of said 20 plate and spaced to freely admit a door between them.

2. A door check comprising a plate pivoted intermediate its ends, a buffer rotatable on a vertical axis at each end of said plate, 25 the axes of said buffers being in a straight line with the axis of said plate and a cushion surrounding each buffer.

3. A door check comprising a pivoted elongated plate with slightly raised ends, a vertical pivot on each of said raised ends, a knob rotatable on each pivot, and a cushion surrounding each knob and projecting over the 30 respective ends of the plate.

4. A door check comprising an intermediate pivoted elongated plate with its ends 35 slightly raised and horizontally disposed, a bolt passing vertically through an opening in each end of said plate a sleeve surrounding each of said bolts, a buffer or knob rotatable on each sleeve and a nut on each bolt adapted to rigidly clamp the sleeve to said plate and prevent the removal of the knob from the sleeve.

5. A door check comprising a thin plate centrally pivoted, a vertical pivot at each 45 end of said plate, and a knob on each pivot having a cylindrical neck and an enlarged head on the upper end of said neck provided with a projecting peripheral cushion.

6. In a door check, a pivoted plate and a 50 pivoted knob on each end of said plate, said buffers being in a straight line with the pivot of said plate combined with a door adapted to swing over said plate having a block with inclined sides secured thereto on one side of 55 the point of contact of said door with the door check when said pivoted plate is in perpendicular relation to the side of the door.

In testimony that I claim the foregoing as my own, I have hereto affixed my signature. 60
in the presence of two witnesses.

WALKER L. PERKINSON.
